UNITED STATES PATENT OFFICE.

WILLIAM E. C. POWELL, OF ALBANY, NEW YORK.

BOTTLE.

1,002,307.

Specification of Letters Patent. Patented Sept. 5, 1911.

Application filed July 22, 1910. Serial No. 573,301.

To all whom it may concern:

Be it known that I, WILLIAM E. C. Powell, a citizen of the United States, residing at 90 Jay street, Albany, in the county of Albany and State of New York, have invented new and useful Improvements in Bottles, of which the following is a specification.

This invention relates to bottles and more particularly to dispensing bottles adapted for use in serving heavy liquids such as catsups, syrups, sauces, etc., and the object of the invention is to provide a bottle for such a purpose which will permit the ready removal of the neck for cleansing without disturbing the contents of the bottle.

A further object of the invention is the provision of a construction of this character of simple and efficient design whereby unskilled persons may readily and quickly separate or put together the different parts so as to form a complete bottle or so that the neck may be readily cleansed.

An independent object of the invention is the provision of a bottle of this type which may be shipped in separate parts so as to avoid breakage which is considerable in shipping long-necked bottles and to obviate the use of extremely large packing cases which are necessary for shipment of long-necked bottles.

Further objects of the invention will appear as the following specific description is read in connection with the accompanying drawing which forms a part of this application, and in which:

Figure 1 is a perspective view of a bottle body. Fig. 2 is a similar view of the detached neck adapted to be used in connection therewith. Fig. 3 is a perspective view of the collar used in connection with the body and neck shown in Figs. 1 and 2. Fig. 4 is a vertical sectional view taken through the stub neck of the bottle shown in Fig. 1 after the collar is attached.

Referring to the drawings and more particularly to Figs. 1 and 2, 1 represents the

body of the bottle which may be of any suitable shape and which is cast or molded of glass or other material and is provided with a stub neck 12. The stub neck 12 and the main neck 13 are provided with a pair of diametrically opposite grooves 14 which are adapted to receive the internally arranged diametrically opposite ribs 15 on the attaching collars 16 and 17. The collar 16 is secured over the stub neck 12 so as to leave a considerable space between the collar and the neck for the reception of cement and the collar 17 is secured to the main neck 13 in a similar manner. As shown, the collar 17 is provided with internal threads 18 adapted to screw upon the external threads 19 formed on the collar 16. In all places where cement is required to connect the parts together, the most approved methods are adapted for causing the cement to obtain a firm grasp upon the glass and metal, one of said methods consisting in roughening the glass by a sand blast. In forming the joint between the main and stub necks the parts are ground flat so that there will be no leakage between the joints and permitting the liquid to flow through the neck unobstructed.

Having thus described the invention, what is claimed is—

A bottle comprising a body having a stub neck thereon, a collar having internal ribs thereon, said stub neck having means to receive the ribs to prevent disengagement of the collar from the stub neck, said collar loosely fitting the stub neck to form a space, cement in said space, a main neck, a collar positioned thereon and having internal ribs, said main neck having means to receive the ribs, and means to connect the collars together.

In testimony whereof I affix my signature in presence of two witnesses.

WILLIAM E. C. POWELL.
